CHURN SUPPORT

Arthur H. Boileau, Cedar Rapids, Iowa, assignor
to Cherry-Burrell Corporation, Wilmington,
Del., a corporation

Original application January 3, 1939, Serial No.
249,056. Divided and this application February
24, 1944, Serial No. 523,754

5 Claims. (Cl. 259—81)

1

This invention relates to churns and butterworkers. More particularly, the invention relates to the arrangement of elements for satisfactorily supporting churns and butterworkers of the sanitary type, having a horizontal, rotatable drum provided interiorly with fixed shelves and baffle means for the agitation, blending and working of the cream and butter.

In churns and butterworkers of the sanitary type when constructed of wood, distortion and warping of the wood may frequently occur. It is, therefore, essential that the construction be such as to prevent objectionable warping or that allowances be made for such possible distortion or warping of the drum and drum head or ends of the assembled churn drum to prevent the development of undue strains in the supporting and driving mechanism, which strains are normally brought on by such distortion or warping. It is also desirable in the construction of sanitary wooden churns and butterworkers to avoid as much as possible the use of exposed metal parts, packing glands or other similar elements on the interior of the churn, which elements may present unsanitary surfaces and which, if not meticulously cleaned, constitute sources of contamination of the product manufactured in such churns and butterworkers.

The accompanying drawings illustrate the aspects of the improved design in a support arrangement for a churn and butterworker which is a simple and inexpensive construction as contemplated by this invention. However, the invention is not to be limited to the specific embodiment disclosed. The features of the improved churn and butterworker illustrated in the accompanying drawings, which features relate particularly to the novel shelves or baffles and to the particular arrangement thereof within the drum of the churn and butterworker, are described and claimed more specifically in my co-pending application Serial No. 249,056, now Patent 2,359,744 dated October 10, 1944, entitled "Churn and butterworker," which application was filed January 3, 1939, and of which application this is a division.

The objects of this invention are to provide a simple, inexpensive, sanitary churn and butterworker of durable construction, in which the shelves and baffles within the churn are rigidly supported and held in place and so arranged as to efficiently blend, combine, uniformly mix and work the cream and butter being processed; in which a centrally positioned baffle or splitting bar is rigidly supported and cooperates with the pe-

2

ripheral baffle or shelves to facilitate the blending operations performed upon the product; in which the drum of the churn and butterworker is so supported upon the standards, and the shelves or baffles and splitting bar so supported within the churn as to maintain the interior of the drum of the churn and butterworker substantially free of exposed metal parts; and in which the means supporting the drum of the churn and butterworker upon its standards provides for the avoidance of possible damage which would normally result from warping or distortion of the elements of the drum of the churn and butterworker.

The particular object of this invention is to provide an improved churn and butterworker, comprising a cylindrical, horizontally disposed, rotatable churn and butterworker drum, having a plurality of longitudinally extending, fixedly mounted shelves within the drum intermediate the end walls or heads of the drum.

A further object of this invention is to provide an improved arrangement of elements for supporting the drum of the churn and butterworker in such a manner as to accommodate expansion, contraction, distortion or warping of the drum of the churn and butterworker without producing or applying substantial stresses or strains in the supporting and driving mechanism, and which will also form a rigid, unitary construction of the churn drum heads, shelves, baffles and supporting spider or gudgeon independent of the standard on which the assembled drum is ultimately supported in operative position.

Another object of this invention is to provide a unique manner of supporting the churn drum, drum heads and shelves upon the churn gudgeons or supporting spiders and to support the shelves or baffles within the churn by the same unique arrangement, whereby the use of exposed metal parts within the interior of the drum of the churn and butterworker is avoided.

Other important features of this invention will be more apparent upon the examination of the details of the construction of the improved churn and butterworker, including the alternative arrangements or construction for supporting the shelves or baffles within the drum of the churn and butterworker, in which arrangement these parts cooperate in a novel manner with the gudgeons or supporting spiders, all of which may be varied within certain limits without departing from the spirit and scope of the instant invention. The invention will be clearly described in the following description and the appended claims, ref-

erence being made to the accompanying drawings in which:

Figure 1 is a perspective view of a horizontally disposed, rotatable churn and butterworker drum, constructed in accordance with this invention and provided with the conventional type of standard and driving mechanism.

Figure 2 is another perspective view, similar to Figure 1, and embodying the invention, and in which the staves constituting the front portion of the drum of the churn and butterworker have been removed to more clearly illustrate the interior construction of the drum, including the shelves or baffles, the splitting bar and their relative positioning within the interior of the drum and the general arrangement of the supporting mechanism.

Figure 3 is a transverse, sectional elevation taken along line 3—3 of Figure 2.

Figure 4 is a perspective view, partially in broken-away section, of an interior portion of the drum of the improved churn and butterworker, illustrating particularly the manner of mounting a shelf supporting bracket on the interior of the end of the drum, i. e., the drum head, as well as the manner of mounting the shelves or baffles upon such brackets and the mounting of the assembled drum, drum heads, shelves and splitting bar upon the supporting gudgeon or spider.

Figure 5 is a fragmentary, longitudinal, sectional elevation of a portion of the end of the central splitting bar and the immediately adjacent portion of the drum. This view is taken generally along the central line of the splitting bar and illustrates the method of fixedly supporting the splitting bar within the drum of the churn and butterworker.

Figure 6 is a fragmentary, sectional view taken through the shelf supporting bracket, the drum head and the end of the supporting gudgeon and end of the shelf when these various elements are in operative arrangement. Figure 6 is a view taken along the line 6—6 of Figure 8.

Figure 7 is a fragmentary, sectional view, illustrating an alternative construction for supporting the shelves or baffles within the drum of the churn and butterworker and the drum head upon the gudgeon or spider, whereby the shelf supporting bracket, as illustrated in part in Figure 6 is eliminated.

Figure 8 is a fragmentary, sectional view taken longitudinally through the bracket end of the churn supporting gudgeon, drum head and shelf supporting bracket along the line 8—8 of Figure 6.

Referring to the illustrations of the preferred embodiment of the invention in an improved churn and butterworker support arrangement for use preferably in a horizontally disposed, rotatable drum type of churn and butterworker, as illustrated in the drawings, the invention includes a cylindrical wooden drum of the conventional stave type generally, identified by the numeral 11. The drum or cylinder 11 is provided with opposed drum or cylinder heads or end walls 12 and 13. Suitable drum stave confining bands or hoops 14, provided with tightenable turnbuckles 15, are placed about the outer periphery of the drum 11 at spaced intervals.

A novel improvement embodied in the invention is the manner in which the drum or cylinder 11, which is composed of independent staves, is supported at its ends by means of the cylinder ends or heads 12 and 13, which coact with the

opposed supporting spiders or gudgeons in such a manner as to avoid the use of exposed metal parts within the interior of the cylinder or drum 11. To thus support the assembled drum 11, drum heads 12 and 13, as well as the interior shelves, there are provided bracket blocks 17, each of which blocks is internally provided with suitable bolt anchorage, such as a metal rod 18, having several drilled or tapped openings 19. The rod 18 in each instance is sealed into the longitudinally extending opening 20 of the associated block 17 by stoppers 21, all as clearly illustrated in Figures 6 and 8. The respective bracket blocks 17 are fitted into recesses 22 in the interior faces of the cylinder heads or end walls 12 and 13. The tapped holes 19 in the bolt anchorage 18 are arranged perpendicularly to the plane of the end wall 12 or 13 and are in alignment with the anchor bolt openings 23 through the adjoining portion of the bracket block 17 and the corresponding openings 24 in the end walls or drum heads 12 or 13. Each of the opposed drum supporting spiders or gudgeons includes a central hub 25, mounted in any conventional manner upon a trunnion (not shown) and having a plurality of substantially radially extending arms 26, each of which arms is provided with an elongated terminal 27, having anchor bolt openings 28 corresponding to and in alignment with the corresponding openings 24 in the end wall 12 or 13. Each gudgeon is fixed to the associated bracket blocks 17 on the interior of the drum heads by means of anchor bolts 29, each of which bolts passes through the aligned corresponding openings 28, 24 and 23 into a tapped opening 19 to engage the associated anchor rod 18. The spider or gudgeon does not directly engage any portion of the drum 11. The drum 11 is supported upon the drum heads or cylinder ends 12 and 13, which engage the supporting spiders or gudgeons.

The trunnions (not shown) to which the drum support and gudgeons or spiders are fixed by means of the hubs 25 may be supported in any conventional manner. In the embodiment of the invention as illustrated in Figures 1 to 8, inclusive, there is shown a supporting arrangement for the drum of the churn and butterworker similar to the arrangement disclosed in the United States Patents No. 1,805,464 and No. 1,805,753. In general, the trunnions cooperating with the supporting spiders or gudgeons are mounted in any conventional type of journal in a standard, in which the journal is provided with end thrust features and in which the bearings are carried at the upper portion of the standards, such as the standards 30 and 33. As illustrated, the trunnion, coacting with the supporting spider or gudgeon fixed to the end wall 12, is carried by a suitable drive unit fixed to the standard 33, which drive unit is generally indicated by the numeral 32. Tubular bracing elements 31 join the lower portions of the vertical standards 30 and 33 to complete the rigid framework or base for the improved churn and butterworker.

In fixing the supporting spiders or gudgeons to the end walls or drum heads 12 and 13 of the drum 11, as above described, it is to be observed that the use of exposed metal parts on the interior of the churn drum has been entirely avoided and that the resulting structure, consisting of the gudgeons or spiders, drum heads and shelves, independently forms a rigid unitary structural assemblage. Such a construction is

desirable in that it prevents the objectionable exposure of metal parts on the interior of the drum of the churn and butterworker and further provides various advantageous structural or operative features. The presence of exposed metal parts within the drum of a wooden churn and butterworker, particularly when such metal parts are in contact with the wood, tends to cause deterioration of the wood, as well as the metal, which deterioration when present may have a detrimental effect on the quality of the product or products produced in a churn and butterworker. It is, of course, needless to indicate that the interior of the drum of the improved churn and butterworker, as illustrated in the drawings, may be readily and easily cleaned and the deterioration of the drum heads and shelves of the improved type of churn prevented when the elements used in the aforescribed supporting arrangement do not include the use of exposed metal parts on the interior of the churn. The present type of structural arrangement, as just described, accomplishes this objective, as well as providing a very rigid drum, drum head and shelf arrangement, in which the drum heads and shelves are compressed between the opposed gudgeons.

The invention contemplates the use of shelves or baffles for the agitation, working and blending of the cream and butter being processed within the improved churn and butterworker. The improved shelves and the arrangement thereof are clearly set forth in the co-pending application, Serial No. 249,056, of which this is a division.

As shown in Figures 2, 3 and 4 of the drawings, the drum of the improved churn and butterworker is provided with a plurality of closed face or imperforate agitation shelves or baffles 34, 35 and 36, the ends of which are supported on brackets 17 on the inner face of the drum heads or end walls 12 and 13 of the drum 11. The shelves or baffles are braced intermediate their ends by braces 37 fixed to the interior of the longitudinal wall of the drum 11. The shelves 34, 35 and 36 are spaced slightly from the inner periphery of the drum 11, but are supported upon the brackets 17 and braced by the brace 37. The rear edge of each of the shelves 34, 35 and 36 is parallel to the adjacent wall of the drum 11. The shelves 34, 35 and 36 are not radially disposed with respect to the longitudinal axis of the drum 11 but instead the shelves 34 and 35 are angularly arranged with respect to the radii of the drum 11. The shelf 36, which is the "unloading shelf" is also angularly disposed in a manner similar to the shelves 34 and 35. The rear edges of all of the shelves are equally spaced relative to the inner surface of the drum 11 and are spaced equally from one another.

The improved churn and butterworker is provided with a splitting bar or central baffle member 38 supported substantially centrally within the drum 11. The bar 38 is preferably of circular cross-section and extends along the longitudinal axis of the drum. The bar 38 is rigidly fixed at each end to the adjacent drum head or end wall 12 or 13 by a bolt 39 which passes through the adjacent end wall and is anchored to the metal cross bar 40 imbedded in the adjacent end of the baffle or splitting bar element 38. The crossbar 40 is sealed in the end of the bar 38 by stoppers 41, as clearly shown in Figure 5 of the drawings. The splitting bar or baffle 38 is positioned in the churn drum in such relation to the shelves 34, 35 and 36, so as to cooperate with them in the

working, blending and agitation of the cream and butter being processed.

For determining the progress of the churning operation, inspection windows or indicators 54 are provided at either end of the drum 11. When the working operation of the butter is completed, it is, of course, desirable and necessary to accumulate the same on the wide or unloading shelf immediately ahead of the churn door. When the working operation is completed, the churn is stopped with the door 42 in the unloading position, as illustrated generally in Figure 1 of the drawings, and the churn is locked in this position by a swiveled pawl 43 mounted on the tubular frame element 31 by the clamp 44. The locking is accomplished by engaging pawl 43 with the rack 45 mounted on the adjacent end of the drum 11 by bolts 46. To facilitate emptying the drum 11 there is provided a conventional type of discharge outlet 55 mounted in one of the end walls or drum heads 12 or 13 of the drum 11 adjacent the outer periphery thereof.

An important feature of the invention relates to the manner of supporting the ends of the shelves or baffles in the churn barrel, whereby the shelves are removable and rigidly supported without the use of any exposed metal parts. The shelf supporting arrangement shown in Figures 6 and 8 involve the use of the bracket 17 at each end of the shelf. The bracket 17 is partially fitted into a corresponding recess 22 in the end wall 12 or 13 of the drum 11. The bracket 17 is held rigidly in place by the gudgeon anchor bolts 29, which are fixed to the anchor bar 18. The shelves resting upon the brackets 17 are fixed thereto by the countersunk bolts 47 extending through the shelves into the brackets 17 and suitably threaded into the bolt anchorage 18 housed within an opening in each of the brackets 17. Stoppers 48 are fitted into the countersunk openings of the shelves to seal therein what would otherwise be an exposed metal surface of the bolts 47.

An alternate construction for the supporting of the shelves in the churn barrel is shown in Figure 7 of the drawings. In the alternate construction shown in Figure 7, each of the brackets 17 is replaced by an end of one of the shelves 34, 35 or 36. By fitting such replacing end of a shelf, as, for example, shelf 34', tightly into the recess 16 the likelihood of splitting the end of such a shelf by tightening the associated bolts 29, which tightening applies pressure to the bolt anchorage 18' provided in an inner opening in such end of the shelf, is substantially avoided. In this alternative construction, it is, of course, not necessary to separately fix each end of the shelf to its associated bolt anchorage 18' as is necessary in the preferred type of construction which is illustrated in Figure 6 of the drawings.

Mounting the various shelves of the improved churn and butterworker upon the brackets 17, to which the churn supporting spider or gudgeon terminals 27 are fixed, provides an extremely satisfactory and economical arrangement for supporting the drum, drum heads and shelves of a churn and butterworker. As is clearly illustrated in Figure 3 of the drawings, the anchor bolts 29, which secure the spider terminals 27 to the bracket blocks 17, are not arranged in parallel alignment with the grain of the wood of the end walls or cylinder heads 12 and 13. This is obvious upon an examination of the arrangement of the bracket 17 into which the anchor bolts 29 extend after passing through the drum heads or cylinder

heads 12 or 13. By avoiding such parallel alignment, the possibility of splitting the end walls or cylinder heads 12 and 13 due to impact strain caused by the dropping of cream or butter upon the shelves or baffles during the churning operation is substantially minimized.

The improved arrangement for use in a churn and butterworker, as herein described, provides a very simple and efficient construction for the rigid support of the shelves or baffles, drum head and cylinder of a churn and butterworker. There are no relatively movable parts within the improved churn and butterworker and exposed metal parts within the interior of the churn barrel, common in a conventional type of churn, have been entirely avoided. The novel manner of mounting the drum heads and shelves of the churn and butterworker directly upon the supporting spiders or gudgeons by securing the terminal ends or pads at the ends of the arms of the supporting spiders or gudgeons to brackets associated with the drum heads, which brackets also support the shelves in the interior of the drum, or the fixing of such terminal pads directly to the ends of the shelves is a decided improvement over the support arrangement used in the conventional type of churn. The improved arrangement for supporting the drum heads and shelves directly upon the gudgeons or spiders also provides a structural design in which the rigid, well-braced, interlocked construction is secured between the supporting gudgeons, the drum heads and the churn shelves or baffles entirely independent of the drum or cylinder. By virtue of this improved construction, it is possible to readily remove defective shelves or baffles from the supporting brackets and replace the same by new shelves without completely dismantling any other portion of the assembled churn. In the conventional type of churn construction appreciable dismantling of the churn is necessary to permit the replacing of shelves within the churn drum.

It will, of course, be understood that various detail alterations and arrangements of the principal elements which have been described and which have been illustrated in the accompanying drawings may be made by those skilled in the art within the scope of the invention as set forth in the appended claims.

The invention is hereby claimed as follows:

1. A device of the class described comprising a cylinder, cylinder heads for said cylinder, rotatable supports for rotatably supporting said cylinder and said cylinder heads, a shelf within said cylinder, and bracket means common to said shelf and said cylinder heads for supporting said shelf within said cylinder and for supporting said cylinder heads upon said supports, whereby said shelf may be readily removed from said bracket means without dismantling said cylinder.

2. A device of the class described comprising a cylinder, cylinder heads for said cylinder, rotatable supports for rotatably supporting said cylinder and said cylinder heads, a shelf within said cylinder, bracket means common to said shelf and said cylinder heads for supporting said shelf within said cylinder and for supporting said cylinder heads upon said supports, whereby said shelf may be readily removed from said bracket means without dismantling said cylinder.

5
8
der heads upon said supports, and separate means for removably attaching said shelf to said bracket means, whereby said shelf may be readily removed from said bracket means without dismantling said cylinder.

10
15
3. In a churn and butterworker, a rotatable drum, rotatable supports for rotatably supporting said drum, flat butterworker shelves within said drum and independent of said drum and extending from end to end of said drum, said shelves varying in width substantially throughout their entire length, a flat unloading shelf of uniform width within said drum and extending from end to end of said drum, and means supporting at least some of the shelves upon said drum supports independent of said drum.

20
25
4. In a churn and butterworker, a rotatable drum, rotatable supports for rotatably supporting said drum, flat butterworker shelves within said drum and independent of said drum and extending from end to end of said drum, said shelves varying in width substantially throughout their entire length, and means supporting said shelves upon said rotatable supports independent of said drum whereby shelf support strains imposed upon said shelves are directly transmitted to said rotatable supports.

30
35
5. In a churn and butterworker, a pair of cylinder ends, a cylinder encompassing and mounted on said cylinder ends, rotatable supports for rotatably supporting said cylinder ends, flat butterworker shelves within said cylinder and extending from cylinder end to cylinder end and spaced from said drum remote from the longitudinal axis of said cylinder, said butterworker shelves being wider at an end than at their midsection and varying in width throughout substantially their entire length, bar means extending adjacent the longitudinal axis of said cylinder from end to end thereof, a flat unloading shelf of uniform width within said cylinder and extending from cylinder end to cylinder end and spaced from said cylinder remote from the longitudinal axis of said cylinder, and means for directly and rigidly supporting the shelves upon said rotatable supports, whereby the shelves are rigidly supported in spaced relation to said cylinder to permit the ready passage of fluid material through between said shelves and said cylinder and whereby the shelves of varying width coact with said bar means to urge the butter being worked within said cylinder toward the mid-portion of the cylinder.
